DESIGN FOR A HELICOPTER

Richard H. Prewitt, Lansdowne, Pa., assignor to
Kellett Aircraft Corporation, a corporation of
Delaware

Application September 7, 1944, Serial No. 115,217

Term of patent 14 years

(Cl. D71—1)

To all whom it may concern:

Be it known that I, Richard H. Prewitt, a citizen of the United States, residing in Lansdowne, in the county of Delaware and State of Pennsylvania, have invented a new, original, and ornamental Design for a Helicopter, of which the following is a specification, reference being had to the accompanying drawings, forming a part thereof.

Fig. 1 is a front perspective view of the helicopter embodying the new design;

Fig. 2 is a top plan view;
Fig. 3 is a front elevational view; and
Fig. 4 is a rear elevational view thereof.
In Figs. 2, 3 and 4, portions of the propeller blades are broken away for convenience of illustration.

I claim:
The ornamental design for a helicopter, substantially as shown.

RICHARD H. PREWITT.
